UNITED STATES PATENT OFFICE

MAX SHEAR, OF KANSAS CITY, MISSOURI.

FOOT REST

Application filed December 5, 1930. Serial No. 500,233.

The present invention relates to foot rests and particularly adjustable rests which are made up of a base and a slide member, movable with respect to each other, to and from the inoperative position.

Foot rests of this kind are used to support the feet of customers in such places as shoe shining parlors, shoe sales rooms, and other places where it is desired to dispose the feet 10 of the customer in a suitable position for action thereon by the proprietor. It is well known that adjustable foot rests of this general character must be constructed with a minimum number of parts and in a manner 15 permitting them to be assembled without the use of complicated interengaging mechanism. Also, the foot rest should be operable quickly and should be especially strong and rugged.

20 One of the primary objects of this invention is to provide a foot rest of the above-mentioned character which is provided with a base and a slide which will not accidentally come apart when the foot rest is in use. To 25 carry out this point of invention it is desirable to interlock the two parts making up the foot rest while they are entirely removed from the operative relation.

The specific points of invention embodied in this foot rest will be set forth during the course of the following specification, referring to the accompanying drawing, wherein:

Figure 1 is a side elevation of a foot rest embodying this invention.

Fig. 2 is a top plan view of the same.

Fig. 3 is a vertical central longitudinal section through one part of the foot rest, showing said part raised to a position where it may be removed from the operative relation with the other part.

Fig. 4 is a vertical cross section taken on line IV—IV of Fig. 3, and greatly enlarged for clearness, and.

Fig. 5 is a vertical cross section taken along line V—V of Fig. 3.

Referring to the specific parts of the foot rest, the numeral 8 indicates a base which may be firmly secured in place beneath the seat not here shown. Base 8 is preferably formed in cross section as shown in Figs. 4

and 5 to present a longitudinal groove 10 along each side thereof, which terminates at one end of base 8 as shown in Fig. 3. At this end each groove 10 extends upwardly at an angle to form a passage 12. A shoulder is formed at the juncture of passage 12 and groove 10 for a purpose herein more fully set forth. The opposite end of each groove 10 for a considerable distance inwardly, is inclined downwardly to form an inclined portion 16 which ends at the stop 18. 55 60

Slide 20 is coextensive with base 8 and is formed to present a depending wall 22 along each side thereof which drops down on either side of base 8 and across grooves 10 as illustrated in Fig. 4. The distance between walls 22 is greater than the width of base 8 to allow free relative sliding movement when slide 20 is drawn longitudinally along base 8 to move the platform 24 to or from the closed position shown in Fig. 3. Walls 22 are joined by an end wall 26 which forms an additional stop to limit the movement in one direction of the slide. 65 70

To hold the foot rest rigid when pressure is exerted on platform 24 in the direction of the arrow shown in Fig. 1, and yet to allow easy relative movement between the two, a pair of rollers 28 is carried by slide 20, adjacent one end thereof. As illustrated in Figs. 4 and 5, one roller is carried by each depending wall 22 by a trunnion 40, formed integrally therewith and extending inwardly toward the base 8 into the adjacent groove 10. 75 80

A roller 28 is carried by each trunnion and when the slide 20 is moved along the base 8 this roller engages the bottom of its groove 10 until the desired adjustment is made, at which time a downward pressure on platform 24 causes the roller to move against the upper wall of its groove 10. 85 90

To limit the movement of slide 20 along base 8 in one direction, the rollers strike stop 18 and to limit the movement in the other direction stop 26 strikes the end of base 8 as shown in Fig. 3. The inclined portion of each groove 10 allows the slide and platform 20 and 24 respectively to drop slightly when the rollers reach that portion. This action is de- 100

sired when the device is being adjusted for a person with long legs.

One of the very important features of this invention is a possibility of assembling the 5 foot rest in a manner which will preclude accidental displacement of any part thereof during its use. When stop 26 has limited the movement of slide 20 in one direction, rollers 29 lie against shoulder 14. To entirely remove 10 slide 20 from the base 8 it is absolutely necessary to lift the same to a position shown in the dotted lines of Fig. 3. After the stop 26 has been moved out of its operative position the rollers 28 may be then disengaged from 15 the groove 10 by moving the entire slide 20 rearwardly and upwardly to cause the rollers to move along the angled passage 12. A part of the top wall of slide 20 above rollers 28 is 20 cut away as shown in Figs. 2, 3 and 5 to allow such assembling and disassembling action as has just been set down.

It will be obvious from the foregoing that the relative positions assumed by the parts of this foot rest will never be such that accidental 25 displacement can occur. This novel feature overcomes the heretofore well known objection that at certain points of adjustment the slide 20 would fly out of position to cause injury or otherwise discomfort both customer 30 and proprietor of a shop using the device.

Having thus described the invention, what is claimed as new and desired to be secured by Letters Patent is:

1. A foot rest comprising in combination, a 35 co-extensive base and slide, a longitudinal groove formed along each side of the base, a depending slide wall on each side respectively of the base, a stop at one end of the slide and a roller carried by each depending wall 40 respectively at the other end of said slide disposed to travel in the adjoining groove as the slide is moved longitudinally of the base, said stop functioning to limit the said movement before the rollers reach the end of said 45 grooves.

2. A foot rest comprising in combination, a co-extensive base and slide, a longitudinal groove formed along each side of the base, a depending slide wall on each side respectively of the base, a stop at one end of the slide 50 positioned to strike said base when said slide walls are embracing the base, a roller carried by each depending wall respectively at the other end of said slide disposed to travel in the adjoining groove as the slide is moved longitudinally of the base, each groove extending upwardly at an angle at their one end to form a passage for said rollers, said rollers being precluded from passing from its 55 groove to the passage when the stop is against the base.

3. In a foot rest, a base, a slide thereon, a longitudinal groove in each side of said base, rollers carried at one end of the slide to travel 60 in each groove respectively, an angled pas-

sage joining each groove at one end thereof, and a stop on the slide to preclude travel of said rollers along said passage when base and slide are in normal relative positions.

4. In a foot rest, a base, a slide thereon, a 70 longitudinal groove in each side of said base, an angled passage joining each groove at one end thereof, a shoulder at the juncture of groove and passage, rollers carried at one end of the slide to travel in the grooves as the slide is moved along the base and a stop to limit said movement, the rollers resting against said shoulders when the stop has limited movement in one direction.

5. In a foot rest, a base, a slide thereon, a 75 longitudinal groove in each side of said base, an angled passage joining each groove at one end thereof, an inclined portion formed by the groove, a stop formed by the base at one end of said inclined portion, to limit movement in one direction, rollers carried at one end of the slide to travel in the grooves as the slide is moved along the base and a stop formed by the slide to limit the movement in 80 the opposite direction.

6. In a base for foot rests, a roller receiving 85 groove in each side thereof having an inclined portion adjacent its one end and an angled passage joining each groove respectively at the other end whereby rollers may be 90 introduced into said grooves.

In testimony whereof, I hereunto affix my signature.

MAX SHEAR.
